US00D665009S

(12) **United States Design Patent**
Nibauer et al.(10) **Patent No.:** **US D665,009 S**
(45) **Date of Patent:** **** Aug. 7, 2012**(54) **SPECTACLES FRAME**(75) Inventors: **Lisa Nibauer**, Short Hills, NJ (US);
Evelyne Chaubert, San Francisco, CA (US);
Blake Shige Kuwahara, Sausalito, CA (US)(73) Assignee: **Adlens Beacon, Inc.**, Iselin, NJ (US)(**) Term: **14 Years**(21) Appl. No.: **29/412,594**(22) Filed: **Feb. 6, 2012****Related U.S. Application Data**

(60) Division of application No. 29/380,473, filed on Dec. 6, 2010, which is a continuation of application No. 12/904,769, filed on Oct. 14, 2010.

(51) **LOC (9) Cl.** **16-06**(52) **U.S. Cl.** **D16/326**; D16/325; D16/335; D16/309(58) **Field of Classification Search** D16/101, D16/300-342, 900; D29/109-110; D24/110.2; 351/41, 44, 51-52, 62, 158, 92, 103-123, 351/140, 153, 45-46; 2/426-432, 447-449, 2/441, 434-437, 13, 15; D21/483, 659-661; D14/372

See application file for complete search history.

Primary Examiner — Raphael Barkai(74) *Attorney, Agent, or Firm* — Sterne, Kessler, Goldstein & Fox P.L.L.C.(57) **CLAIM**

The ornamental design for a spectacles frame, as shown and described.

DESCRIPTION

FIG. 1 is a front right perspective view of a spectacles frame showing our new design;

FIG. 2 is a front left perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.
